CLAIM

The ornamental design for a lottery ticket, as shown and described.

DESCRIPTION

FIG. 1 is the sole plan view of a first embodiment of a lottery ticket, the ticket being of no appreciable thickness; and, FIG. 2 is the sole plan view of a second embodiment of a lottery ticket, the ticket being of no appreciable thickness. All broken lines are for illustrative purposes only, and form no part of the claimed design.

1 Claim, 1 Drawing Sheet

FIG. 2

FIG. 1
